(57) **CLAIM**

The ornamental design for a surface pattern for a paper product, as shown and described.

DESCRIPTION

The sole FIGURE is a top plan view of a surface pattern for a paper product, showing our new design. The broken lines in the FIGURE from no part of the claimed design and represent the boundaries of one repeat unit of the claimed surface pattern as well as a portion of the paper product to which the pattern is applied. It is understood that the claimed design repeats uniformly in one or more directions.
